(57) **CLAIM**

The ornamental design for a fan housing, as shown and described.

DESCRIPTION

FIG. 1 is a front perspective view of a fan housing showing my new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a left side elevational view thereof; and,

FIG. 7 is a right side elevational view thereof.

The broken line showing of portions of a fan is included for the purpose of illustrating environmental structure and forms no part of the claimed design.
